Primary Examiner — L. Martinez(74) *Attorney, Agent, or Firm* — K&L Gates LLP; Louis C. Cullman; Brian J. Novak(57) **CLAIM**

The ornamental design for a band, as shown and described.

DESCRIPTION

FIG. 1 is a perspective view of a first embodiment of a band showing our new design.

FIG. 2 is a front view of the band of FIG. 1.

FIG. 3 is a rear view of the band of FIG. 1.

FIG. 4 is a top view of the band of FIG. 1.

FIG. 5 is a bottom view of the band of FIG. 1.

FIG. 6 is a first side view of the band of FIG. 1.

FIG. 7 is a second side view of the band of FIG. 1.

FIG. 8 is a perspective view of a second embodiment of the band showing our new design.

FIG. 9 is a front view of the band of FIG. 8.

FIG. 10 is a rear view of the band of FIG. 8.

FIG. 11 is a top view of the band of FIG. 8.

FIG. 12 is a bottom view of the band of FIG. 8.

FIG. 13 is a first side view of the band of FIG. 8; and,

FIG. 14 is a second side view of the band of FIG. 8.

The broken lines shown in the figures represent portions of the band that form no part of the claimed design.
